MULTIFORM ENVELOPE

Victor J. Sawdon, Tuckahoe, N. Y.

Application July 16, 1936, Serial No. 90,864

7 Claims. (Cl. 229—92.7)

This invention relates to a multiform envelope, especially to a form of envelope adapted to be mailed in large quantities, each envelope being provided with means to facilitate the disposal of a return reply, and more particularly the invention relates to a mailable item of the class in which a portion of the original structure is to be detached by the recipient prior to despatch of the return envelope.

10 An object of the invention is to provide such a multiform mailable item with an envelope component which has a partially open structure permitting postal inspection in its originally mailable condition, so that it can be mailed as a postal item of relatively inferior class, and which is so disposed that with little voluntary effort on the part of the recipient, the sealing of the envelope in conventional fashion for return mailing will automatically convert it into a 20 first class mailing item.

Such an item, by reason of the nature of its contents, and the fact that it has been sealed, will require the payment thereon of appropriate postage, which may be of the so-called free return type, the return postage having been provided for by the original sender, as indicated on the face of the return envelope, or the return postage may be prepaid by the recipient when he mails the return envelope.

30 Another object of the invention is to provide a return envelope of the above character in which the name and address of the recipient-addressee may be typed, or otherwise inscribed, in alignment with a window opening through which the addressee's name, etc., is visible at the 35 time of the first mailing, and which is thereafter so folded-in as not to be in evidence at the time of return mailing, the aforesaid name and address being however so disposed, preferably 40 upon a portion of the sealing flap or adjacent part of the envelope that it will be available for reference without any written addition by the person returning the envelope, who will nevertheless be likely to see it before re-mailing, and 45 will be stimulated thereby to make any correction of name, address or other legend, which he may consider to be necessary or desirable.

Other objects and advantages of the invention will appear as the description of the particular physical embodiment of the invention selected for illustration herein progresses, and the features of novelty will be pointed out.

Like characters of reference have been applied to corresponding parts throughout the sev-

eral figures which make up the accompanying drawings, in which:

Fig. 1 is a view in plan of a multiform envelope structure in the fabrication of which the present invention has been embodied;

Fig. 2 is a view of the structure shown in Fig. 1, after it has been folded upon itself along its medial vertical line;

Fig. 3 is a view of the structure of Figs. 1 and 2 as it appears when completely folded for 10 the first mailing;

Fig. 4 is a view like that of Fig. 3, but illustrating the envelope structure as it appears when ready for return mailing after the detachment 15 of a portion of the structure originally mailed to the recipient;

Fig. 5 is a view similar to Fig. 2 of an envelope structure modified by the provision of a window opening through which the name and address of the recipient may be viewed;

Fig. 6 is a view of another modification, like that shown in Fig. 5, but with the window opening in a different position, for viewing a differently disposed address.

In a now-preferred embodiment of the invention selected for illustration and description, the part designated generally by the reference character **E** is an envelope structure comprising a body panel **1**, a bottom flap **2** folded over, and adhered, as at **3**, to the left-hand side of the body panel, and a narrow right-hand flap **4** which is provided with a spot of gum, indicated as a dotted circle at **5**, whereby the flap **4** is held against casual displacement, but can be readily untucked by a postal inspector, at will, when the envelope structure has been folded upon itself a second time, along the line **6**, as shown in Fig. 3, the gummed flap **4** being folded over and adhered. The envelope structure, as shown in Fig. 3, is ready for its original mailing, as a postal item of a relatively inferior class, the position of the flap **4** being clearly shown in Fig. 3, where it is partly revealed, the overlying panel **8** being cut away at **9** for that purpose.

The panel **8** forms part of an integral extension (see Fig. 1) along the entire left-hand margin of the envelope proper, which may desirably be defined by an easy tear line **10** and which includes also a part which, in Fig. 2, appears as a panel **11** adjoining the parts just described, being preferably integrally formed, and co-extensive in height, with the body **1** and cover flap **12**. The upper edge **13** of the extension **11** is provided with the relatively small

45

50

55

55

sealing flap 7 which, as already described, serves to retain the folded structure in mailable condition for the first mailing (see Fig. 3).

The inside continuous surface of the panels 8 and 11 is intended to bear a multiform communication, which may be of various sorts, as for example a request to pay a bill, or to renew a subscription, or to make a donation, or to reply promptly to some stated request or inquiry of the original sender. In Fig. 1, part 10 of a request to make a payment is shown, ending with brief instructions as to the return mailing.

The general purpose of the invention being to 15 provide facilities for response which will reduce to a minimum the need for individual initiative on the part of the recipient, the multiform return envelope structure provides, as at 14, a space to be filled in with the name and address 20 of the recipient. As this is directly in view when the recipient is introducing the desired enclosure into the envelope, preliminary to his return mailing thereof, he will be thereby reminded to fill in his name and address, in order to have the 25 responsive enclosure duly identified with him.

As a further provision in aid of the return mailing, the extension panel 8 or the extension panel 11, one of which will overlie the address when the envelope is folded for the original mailing, 30 may be provided with a window opening 15 as illustrated in Fig. 6.

This makes it possible to view therethrough the address, so that the original sender may type-write or otherwise inscribe the name and address 35 of the recipient at the time of the original mailing and be assured thereby of a correct identification upon its return, thus avoiding the contingency of a lack of identification in the event that the recipient overlooks the need for supplying 40 the same, or wilfully omits to inscribe his name and address. The failure by the donor of a contribution to reveal his identity is an instance of the need for such a provision as that last disclosed, for it is obviously desirable to 45 know the origin of each donation to a fund, in order, first of all, that a complete list of donors may be kept; second, that suitable acknowledgement of the donation may be made; third, that the donor shall not be annoyed by follow-up requests, 50 in the same campaign, for a donation which he has already made; and there is also the desideratum, very important from the standpoint of perennial administration of a charity, for example, that the names of all donors shall be 55 available for further solicitation in subsequent years, and that the current address list shall be complete and correct.

A recipient is more likely to take the trouble to correct an improper address than to make the 60 greater effort involved in supplying his complete name and address, even when every possible indication is provided in the way of spaces and appropriate legends, designed to elicit the information, as shown in Fig. 1.

It will be noted that, alternatively with the disposition of the window shown in Fig. 6, the bottom part of the extension 8 may, as illustrated in Fig. 5, be provided with a window, as at 15', so disposed that when the extension is folded 70 over at the time of original mailing the window 15' will register with a space on the exposed face of the bottom flap 2 at which the address is to be filled in, with the intended purpose that the address shall be utilized for the original mailing. 75 The communication on the inside of the panels

8 and 11 will, of course, be suitably disposed, as shown in Figs. 1, 5 and 6, to avoid interference between it and a window, when a window is provided.

In either the form of Fig. 5 or that of Fig. 6, 5 the name and address of the recipient may be typewritten or otherwise inscribed, by the original sender, either prior to the operation of folding, or through the window when the envelope structure is otherwise completely ready for mailing. 10

By availing of the last-named provision, the 15 sender can address individual envelopes seriatim from an already prepared stack of multiform letters, identical in all respects, with the exception of the names and addresses of recipients, and all 20 ready for mailing, so that by a single operation on each item, it may be completed for mailing, and no time lost by reason of the need for performing folding or other operations.

Each such item will accordingly, as already described, 25 carry with it the desired identification of the recipient, to be availed of in any desired manner upon receipt of the return envelope, which may be of the prepaid return type, suitably indicated, as shown at 17, in dotted lines, in 30 a manner approved by the postal authorities, on the face bearing the name and return address of the original sender (see Fig. 4, at 18, indicating name and address on reverse) or the name and address of any intended addressee for the return item.

The desired sealing of the return envelope may be facilitated not only by providing a gummed area at the forward end of the flap, as at 19 (see Fig. 1), but also by providing lateral gummed 35 areas, as at 20 and 21. The last-named lateral area serves, when the envelope is sealed for return, to adhere the cover flap to the lateral side flap 4, thus constituting the return envelope a 40 first-class mail item, completely private, and as such more suitable for enclosure of checks, etc., or of any private communication which the recipient may desire to send in connection with his response.

The desired sealing as a first-class mail item 45 may be promoted by the provision of such a legend as that illustrated at 22, via, "Seal all around", which is self-explanatory, and attention-arresting.

Of course, by omitting to wet the gum on area 50 21 or by omitting the lateral gummed area 21 entirely, the side flap 4 will be left free to be un-tucked for postal inspection, the other advantages of the return envelope structure remaining available as described. 55

I have described what I believe to be the best 60 embodiments of my invention. I do not wish, however, to be confined to the embodiments shown, but what I desire to cover by Letters Patent is set forth in the appended claims. 65

I claim:

1. An envelope structure comprising a body panel, a bottom flap folded over and adhering along one edge directly to a side edge of the body panel, a side flap loosely associated with the remote side edge of the folded-over bottom flap, and a gummed cover flap adapted to be folded over the upper open edge of the envelope and to be adhered directly to the first-mentioned edge of the bottom flap, and also to be adhered along the bottom margin of said bottom flap, and also at will to said side flap, whereby said envelope can be closed at will to serve as a private mailing item and selectively as an at least partially open item. 75

2. A multiform envelope structure of the class described comprising as elements a complete envelope, including a body panel, a bottom flap folded over and adhered along one side edge to the body panel, a side flap associated with the remote side edge of the folded-over bottom flap, and a gummed cover flap; and an extension panel adapted to be folded flatly over said parts which constitute said complete envelope and adapted to be folded again with, and to enclose, said parts, and means to seal said folded-over extension.

3. A multiform envelope structure of the class described comprising as elements a complete envelope, including a body panel, a bottom flap folded over and adhered along one side edge to the body panel, a side flap associated with the remote side edge of the folded-over bottom flap, and a gummed cover flap; and an extension panel adapted to be folded flatly over said parts which constitute said complete envelope and adapted to be folded again with, and to enclose, said parts, and means to seal said folded-over extension, said last-named means being integral with one edge of said extension, thereby sealing one edge thereof and permitting access to the interior of all parts of said envelope.

15

10

20

25

4. A multiform envelope structure of the class described comprising as elements a complete envelope, including a body panel, a bottom flap folded over and adhered along one side edge to the body panel, a side flap associated with the remote side edge of the folded-over bottom flap, and a gummed cover flap; and an extension panel adapted to be folded flatly over said parts which constitute said complete envelope and adapted to be folded again with, and to enclose, said parts, and means to seal said folded-over extension, said extension being readily detachable from said

30

35

complete envelope, leaving the latter in proper form for return mailing.

5. A multiform envelope structure of the class described, said envelope structure comprising as a component a complete envelope, formed of a body panel and complementary flaps including a sealing flap, said envelope having provision on one face for the name and address of an original addressee, and having on the other face provision for the name and address of a return addressee, 10 said first-named address being so disposed as to be concealed by said sealing flap when said envelope is used as a return envelope.

6. A multiform envelope structure of the class described, said envelope structure comprising as a component a complete envelope, formed of a body panel and complementary flaps including a sealing flap, said envelope having provision on one face for the name and address of an original addressee, and having on the other face provision for the name and address of a return addressee, and a detachable extension panel adjoining said complete envelope and foldable there-over into position covering the face bearing said space for the name and address of the original 20 addressee, said extension having a window suitably disposed to reveal said name and address of the original addressee, so that the last-mentioned name and address may be utilized in the original mailing of said envelope structure to the recipient 25 who is to return the same.

7. A multiform envelope structure as set forth in claim 6 and further characterized by having said window formed in the part of said extension panel which is adapted to extend over the rear 30 face of the bottom flap of the complete envelope.

VICTOR J. SAWDON.
